UNITED STATES PATENT OFFICE.

AUGUST WEBER, SR., OF SCHENECTADY, NEW YORK, ASSIGNOR TO WEBER ELECTRIC COMPANY, OF SCHENECTADY, NEW YORK, A CORPORATION OF NEW YORK.

INCANDESCENT-ELECTRIC-LAMP SOCKET.

1,009,120.

Specification of Letters Patent.

Patented Nov. 21, 1911.

Application filed October 1, 1906. Serial No. 336,842.

To all whom it may concern:

Be it known that I, AUGUST WEBER, Sr., a citizen of the United States, residing at Schenectady, county of Schenectady, and 5 State of New York, have invented certain new and useful Improvements in Incandescent-Electric-Lamp Sockets, of which the following is a specification.

The invention relates to such improvements and consists of the novel construction and combination of parts hereinafter described and subsequently claimed.

Reference may be had to the accompanying drawings, and the reference characters 15 marked thereon, which form a part of this specification. Similar characters refer to similar parts in the several figures therein.

Figure 1 of the drawings is a view in side elevation of my improved incandescent 20 electric lamp-socket without the inclosing case which forms no part of the present invention. Fig. 2 is a vertical cross-section of the same taken on the broken line 2—2 in Fig. 1. Fig. 3 is a bottom plan view of the 25 same as shown in Fig. 1. Fig. 4 is a vertical cross-section of the same taken on the broken line 4—4 in Fig. 3. Fig. 5 is a detached view in perspective of a terminal plate, screw and nut. Fig. 6 is a similar 30 view of the terminal plate alone. Fig. 7 is a view of the nut alone. The last three figures are drawn on a relatively large scale.

My invention relates more particularly to the 35 class of keyless incandescent electric lamp sockets, although it may be employed in key sockets, if desired.

The principal object of the invention is to 40 simplify the assembling and connecting together of certain parts of the interior of the lamp-socket.

Other objects of the invention will appear 45 in connection with the following description.

The interior of my improved lamp-socket 50 has a two-piece insulating base comprising the washers, 3 and 4, formed of porcelain, or other insulating material, upon which is mounted the usual screw-shell, 5, the two washers and screw-shell being all securely 55 held together by a pair of screws, 6, each inserted through alined apertures in the two porcelain blocks or washers and the introverted end-flange, 7, of the screw-shell and the nut, 8, engageable with said introverted flange. The screw-shell, 5, is adapted to

be connected with one side of the electric circuit by means of a terminal plate, 9, the body of which is located in a peripheral recess, 10, formed in the insulating base, and the shank of which is interposed between the end-flange of the screw-shell and the porcelain block, 4, said shank being apertured to receive the screw, 6, whereby said plate is secured rigidly in position when the parts are clamped together by said screw. 60 The block, 4, is properly recessed on its outer face to receive said terminal plate. A second terminal plate, 11, adapted to be connected with the other side of the circuit is located in the peripheral recess, 12, 65 in the porcelain base, with the contact end, 13, of said member projecting through an aperture, 14, formed by cutting away a portion of the screw-shell, 5, and being adapted to form a contact for the central lamp terminal. The shank of the plate, 11, is bent 70 approximately at right angles to the body of the plate and is provided with a transverse recess or groove, 15, formed by a bend in the sheet metal of which the plate is 75 formed, which groove is adapted to receive a projection in the form of a rib, 16, formed on the inner face of the porcelain block, 3, 80 said shank being inserted between the two porcelain blocks of the base and clamped 85 tightly therebetween by means of the screws 6. Each of the terminal plates, 9 and 11, 90 is provided with a binding screw, 17, whereby a circuit wire may be connected therewith.

It is desirable where a binding-screw is 95 used for connecting a circuit wire to a terminal plate to provide means for confining the strands of the wire within proper and safe limits.

In constructing the terminal plate, 11, I 100 employ a comparatively thin, but strong and resilient, sheet-metal, and insert a binding-screw, 17, through an aperture therein into a nut, 21, applied to the back of said plate. This nut, 21, is preferably formed with fingers or lugs, 22, adapted to embrace 105 said plate and project outwardly beyond the same a sufficient distance to confine between them any strands of the circuit-wire not covered by the head of the binding-screw. A third finger or lug, 22, on the nut is adapted to be inserted through an aperture, 23, in the body of the plate, 11, and be slightly headed down or riveted to con- 110

nect said nut and plate together. This third lug or finger, 22, may, however, be left projecting a sufficient distance outwardly from the body of the terminal plate to coöperate 5 with the other fingers or lugs, 22, to confine the strands of the wire.

What I claim as new and desire to secure by Letters Patent is—

1. In an incandescent electric lamp-socket, 10 and in combination, an insulating-base; a screw-shell having an introverted end-flange mounted upon said base; a terminal-plate having a shank interposed between said insulating-base and the flange on said shell, 15 and having means for connecting therewith a circuit-wire; and a screw and nut adapted to engage, one the porcelain-base and the other said end-flange on the shell, said screw passing through alined apertures in said 20 flange, insulating-base, and the shank of said terminal-plate.

2. In an incandescent electric lamp-socket, and in combination, an insulating-base comprising a pair of blocks of insulating material; a screw-shell having an introverted 25 end-flange mounted upon the outer base-member; a terminal-plate having a shank located between said flange and said outer base-member in a recess in the surface of the latter; and a screw and nut adapted to engage, one the inner base-member and the other said flange, said screw passing through alined apertures in said flange, both of said 30 base-members, and the shank of said terminal-plate.

In testimony whereof, I have hereunto set my hand this 26th day of September, 1906.

AUGUST WEBER, SR.
